DESIGN FOR A WATCH BAND OR SIMILAR
ARTICLE

Tobias Stern, Scarsdale, N. Y., assignor to Jacques
Kreisler Manufacturing Corporation, North
Bergen, N. J.

Application December 27, 1948, Serial No. 150,354

Term of patent 14 years

(Cl. D45—4)

To all whom it may concern:

Be it known that I, Tobias Stern, a citizen of the United States of America, residing at Scarsdale, county of Westchester, and State of New York, have invented a new, original, and ornamental Design for a Watch Band, or Similar Article, of which the following is a specification, reference being had to the accompanying drawing, forming a part thereof.

Fig. 1 is a top plan view of a watch band, showing my new design, the conventional end attachments being illustrated in broken lines and the links shown in full lines being repeated throughout the length of the band as indicated by the broken lines across the center;

Fig. 2 is a side elevational view of the band as shown in Fig. 1, and

Fig. 3 is a bottom plan view thereof.

Fig. 4 is a top plan view of a part of the band, the links being in expanded position;

Fig. 5 is a perspective view, on a larger scale, of one of the top links of the band.

I claim:

The ornamental design for a watch band or similar article, as shown and described.

TOBIAS STERN.
